COMBINED DRAWER GUIDE AND LEG SUPPORT FOR FURNITURE

Ellis S. Wilkinson, Mebane, N.C., assignor to Melville Furniture Manufacturing Co., Mebane, North Carolina, a corporation of North Carolina

Filed Oct. 22, 1968, Ser. No. 14,116

Term of patent 7 years

Int. Cl. D6—99
U.S. Cl. D33—1

FIG.1

FIG. 3

FIG. 2

FIG. 4

FIG. 5

FIG. 1 is a front perspective view of a combined drawer guide and leg support for furniture embodying my design;

FIG. 2 is a front elevational view of the drawer guide and leg support of FIG. 1;

FIG. 3 is a left end elevational view of FIG. 2;

FIG. 4 is a right end elevational view of FIG. 2; and

FIG. 5 is a top plan view of FIG. 2.

I claim:

The ornamental design for a combined drawer guide and leg support for furniture, as shown.
